UNITED STATES PATENT OFFICE.

HIRAM ALLTON, OF WILMINGTON, DELAWARE, ASSIGNOR OF ONE-HALF TO
JOSEPH E. HILDRETH, OF SAME PLACE.

LUBRICATOR.

SPECIFICATION forming part of Letters Patent No. 275,971, dated April 17, 1883.

Application filed October 27, 1882. (No model.)

To all whom it may concern:

Be it known that I, HIRAM ALLTON, a citizen of the United States, residing at Wilmington, in the county of New Castle and State of Delaware, have invented certain new and useful Improvements in Lubricators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to that class of lubricators in which a measuring-cup is located between a lubricant-receiver and passages leading to the valve-chests of a locomotive or other engine, said measuring-cup being so combined with steam-ports that when it is properly shifted or set steam is admitted into the same for expelling its contents. A lubricator constructed upon the above-mentioned principle forms the subject-matter of a patent granted 20 to me on the 18th day of June, 1878, No. 204,874; and the object of the present invention is to provide such a construction and combination of devices whereby I am enabled to distribute the oil with greater ease and certainty than 25 heretofore and avoid the condensation of steam in the chamber containing the measuring-cup.

To these ends the invention consists essentially in the combination, with an oil-reservoir, of a hollow shell or cup, which is mounted on 30 a central horizontal axis, and turns or rotates in contact with a vertical face-plate having a large port in communication with the oil-reservoir, and smaller ports in communication with a steam-inlet pipe and passages leading 35 to the valve-chests. The hollow shell or cup operates in a surrounding casing, and has two openings in its face, which serve for the admission and discharge of the oil and steam.

The invention also consists in the construction and arrangement of parts, which will hereinafter be more fully described, and then set forth in the claims.

In the drawings, Figure 1 is a vertical sectional view of a lubricator constructed according to the present invention. Fig. 2 is a front view, showing the face-plate with its various

ports and passages, the measuring-cup and its surrounding casing being detached. Fig. 3 is a perspective view of the measuring-cup, constructed of a single piece or shell. Fig. 4 is a rear view of the base or casting, with its steam-inlet and oil-discharge ports. Fig. 5 is a modified construction of the measuring or feed cup. Fig. 6 is a top view of the base or casting.

The letter A designates an oil-reservoir, which 60 may be of any approved construction, it being provided in the present instance with a transparent tube, a, for indicating the contents of the reservoir and observing the discharge of oil therefrom. The base of the lubricator consists of a body or casting, B, having a screw-socket at its top for the reception of the screw-threaded neck b of the oil-reservoir. The front of the casting or body B is turned smooth, so as to constitute a face-plate, C, which, as is 65 shown in Fig. 2, is of a circular shape. The periphery of the body B in rear of the face-plate C is screw-threaded, and a hollow shell or casing, D, is screwed thereto. This casing contains a hollow cup or cylindrical shell, E, 70 which has a circular front wall, e, corresponding in size and shape with the face-plate C. A stem, F, on the cup E projects through the front end of the casing D, and is packed therat by means of a nut, G, applied to a screw-threaded 75 neck, d, of the casing. A spring, U, serves to press the cup against the face-plate. A port or passage, H, extending in a horizontal direction through the top of the face-plate C, and communicating with the socket of the body B, 80 into which the oil-reservoir is fitted, serves as 85 as the conduit for the oil from the reservoir to the distributing-cup E. On each side of the port H, and below the same, are located smaller ports I J, which serve respectively for the discharge of the oil from the cup E into the passages leading to the valve-chests and for the admission of live steam into the cup E for expelling the contents thereof. The steam-ports 90 J converge or run to an inlet-chamber K 95 formed in the back of the body or casting B, and the mouth of this chamber is screw-threaded, and is designed for the reception of a steam-supply pipe connected with the boiler. The oil-discharge ports I run horizontally 100 through the face-plate C, and communicate with passages at the sides of the body B. Pipes

L, connected with these passages by screw-couplings or otherwise, extend to the valve-chests of a locomotive or other engine, and serve for conducting the lubricating material to the same. The front wall, e, of the cup E is provided with an opening, e^2 , for the admission and discharge of the oil, and with a smaller opening, e^3 , serving as an inlet for steam. The stem F of the cup E, carries a handle or crank, F^2 , which serves for rotating or turning the cup in order to fill the same with oil or discharge the latter into the distributing-pipes. A plate, M, attached to the periphery of the face-plate C by screws or otherwise, has an extension or arm, N, which extends over the periphery of the cup E and serves in conjunction with pins O on said cup to arrest or limit the movement thereof. The cup, as shown in Figs. 1 and 3, is cast of one piece of metal; but I also contemplate making the same of two shells or sections, E⁵, joined together by a screw-connection, as is shown in Fig. 5. In this instance the peripheries of the shells are constructed with nuts or polygonal portions for facilitating the joining thereof.

The operation of a lubricator constructed in the above-described manner is follows, viz: When the measuring-cup or feeder is in its normal position, which is preferably determined by the perpendicular setting of its handle, the large opening in the cup is brought opposite the top or large opening in the face-plate, and the small opening in the cup is closed by coming opposite the solid portion of the face-plate. When the parts are in this position oil is freely admitted into the measuring-cup until it is full. In order to discharge its contents into the pipe leading to the valve-chest at the right side of the locomotive, the handle is seized and the cup turned until one of the stop-pins thereon comes in contact with the arm on the face-plate, when the small opening in the cup is brought in line with the steam-port and the larger opening over the oil-discharge port. The pressure of the live steam admitted into the cup will expel the oil therefrom and force it through the pipe leading to the valve-chest, it being obvious that the steam coming direct from the boiler will be of greater pressure or force than that present in the oil-delivery pipe, hence not preventing the proper feeding of the oil to the valve-chest. In order to supply oil to the valve-chest at the left side of the locomotive or engine, the cup is turned in a reverse direction from that above stated until the other stop-pin arrests the further movement of the cup. The openings in

the latter are then brought opposite the steam-inlet port at the right side of the face-plate and the oil-discharge port at the left side thereof, when the above-described admission of steam, resulting in the discharge of the oil, takes place.

I have in the construction of lubricator shown in the present instance had special reference to the lubrication of the valve-chests of a locomotive-engine by one and the same device. I desire it to be understood, however, that I propose making such changes or modifications, without departing from the spirit of my invention, as will adapt the device for use in connection with a single valve-chest or other part of an engine. For example, the shaft or axis of the measuring-cup is made to pass through the body or casting having the oil and steam ports, and, as will be obvious in a single-acting lubricator, I require only three openings in the face-plate—one at the top for the admission of the oil and two openings arranged in a diagonal line for the admission of the steam into the cup and discharge of the oil therefrom.

Having thus described my invention, what I claim as new, and desire to secure by Letters Patent, is—

1. In a lubricator, the combination of a hollow rotating cup having openings in its vertical front wall and mounted on a horizontal axis, a casing or shell surrounding said cup, and a body or casting having a vertical face-plate provided with openings for the admission of oil and steam and an opening for the discharge of oil and steam, with a lubricant-receiver, and devices, substantially as shown, for turning the measuring-cup, as herein set forth.

2. In a lubricator, the combination of the body or casting having a vertical face-plate, top oil-inlet opening, steam-chamber, passages diverging from the latter, and oil-discharge openings, with the rotating measuring-cup, its surrounding casing, and a lubricant-receiver, substantially as herein set forth.

3. The vertical face-plate having a stop-plate, and the measuring-cup having pins, in combination with the body or base, lubricant-receiver, and casing surrounding the measuring-cup, as herein set forth.

In testimony whereof I affix my signature in presence of two witnesses.

HIRAM ALLTON.
